UNITED STATES PATENT OFFICE.

RICHARD C. NUGENT, OF DAYTON, OHIO, ASSIGNOR, BY MESNE ASSIGNMENTS, TO PHILLIPS, NIMICK & CO., OF PITTSBURG, PENNSYLVANIA.

IMPROVEMENT IN MACHINES FOR FLANGING BOILER-HEADS.

Specification forming part of Letters Patent No. 173,808, dated February 22, 1876; application filed September 25, 1875.

To all whom it may concern:

Be it known that I, RICHARD C. NUGENT, of Dayton, in the county of Montgomery and State of Ohio, have invented certain new and useful Improvements in Machines for Nozzling Flue-Holes in Boiler-Heads; and I do hereby declare that the following is a full, clear, and exact description thereof, which will enable others skilled in the art to which it appertains to make and use the same, reference being had to the accompanying drawings, and to the letters of reference marked thereon, which form a part of this specification, in which—

Figure 1 is a side elevation of the machine. Fig. 2 is a sectional view of a portion of the operating devices.

The object of my invention is to procure a machine for forming nozzles on boiler-heads or plates of metal, to which flues are attached in the usual way, in a simple and rapid manner without subjecting the heads to the liability of strains and flaws, as is the case in most methods now in use for this purpose.

The improvements consist in the novel combination and arrangement of a peculiarly-constructed vertical rotary shaft carrying the forming-tool—an essential element of my invention—with the necessary operating mechanism therefor, the frame-work, and an adjustable clamp for holding the head or plate to be operated on in position, as will be herewith described, and the invention distinctly pointed out in the claims.

Corresponding letters of reference indicate like parts in both figures.

A suitable frame-work, A A, of any desired shape and proportions, upholds a platform, B, and two bearing-beams, C and D, which are securely attached to the sides of the frame, and have journal-bearings in which the journals of the beveled-gear wheels E and F revolve, as represented by the dotted lines a, Fig. 1. G and H are two bearings, in which the shafts I and J are confined. These shafts are provided on their outer ends with gear-wheels K and L engaging with each other, and the fast and loose driving-pulleys M. Their inner ends are provided with the beveled-gear wheels N and O, which engage with the wheels E and F. P represents a hollow

screw-shaft, which engages with a thread cut in the wheel E, and by which it is raised up or down, a spline and groove in the journal-bearing R preventing it from turning. Fitting snugly, but free to revolve, in the screw-shaft P is a solid shaft, S, which passes through the center of the wheel F, from which it receives rotary motion by means of a spline and groove in the usual manner. The top of this shaft is a head, T, having shoulders resting on the top of the screw-shaft P, and at the bottom of the screw-shaft is a collar, m, upon the shaft S, against which the screw-shaft acts to lower the forming-tool. The head T has a square socket, in which the forming-tool U is held. The platform B has a circular opening through it, just over the shaft S, and in this opening is the disk V, having a central orifice just large enough to let the tool U pass through. To each machine belong several disks differing only in the sizes of the central orifices, and which are interchangeable for accommodating the machine to different-sized work. W is a top brace connecting the frames A, and having a central threaded hole, through which a screw, X, works. To the bottom of this screw is attached a bell-shaped clamp, consisting of a bottom annulus, b, of a diameter greater than that of the tool, supported by connecting-arms c. The screw carrying the clamp is worked by means of the hand-wheel Y. The forming-tool U is composed of a shank, d, fitting in the socket of the head T, and easily removed, and of a body of the shape represented, having two parallel disks, e and f, provided with journal-bearings, in which the equidistant rollers g, of which there may be four or more, work. The top disk e is smaller than the lower one, in order that the rollers may be more or less inclined.

It is my purpose to have with each machine several forming-tools, each fitting in the same head, and differing only in proportions according to the character of the work required.

The operation of the machine is as follows: The heated plate or boiler-head, having had circular orifices made as usual, is placed upon the platform with one of the holes directly over the forming-tool. The clamp is brought down upon it and holds it securely in position.

Motion is imparted to the machine from the pulley M, and it will be noticed that the shaft S has a rapid revolution carrying with it the tool U, and the shaft P has a slow upward motion carrying with it the shaft S and also the tool U, so the tool has a very slow upward, but at the same time a rapid rotary, motion. The plate being securely clamped, the tool, as it moves upward, presses upon the overlapping edges of the hole to be nozzled, and gradually turns them upward. The rollers upon the tool always keep the enlarged orifice circular. This is continued until the tool has passed through the plate, when the operation is concluded, and a nozzle or flange will be formed upon the boiler-head. In Fig. 2 this operation is partially represented, *k* representing the boiler-head with the nozzle partially formed.

Having thus fully described my invention, what I claim as new, and desire to secure by Letters Patent, is—

1. The combination of the forming-tool U, shafts P and S, with their bearings and collars, and the bevel-gearing, substantially as described.

2. The removable disk V, in combination with the clamp *b* and *c*, screw X, forming-tool U, shafts P and S, bearings R and D, wheels E and F, and their connecting-gearing, whereby a nozzle can be formed upon a boiler-head or plate of metal, substantially in the manner and for the purpose specified.

I testimony that I claim the foregoing as my own I affix my signature in presence of two witnesses.

RICHARD C. NUGENT.
